UNITED STATES PATENT OFFICE.

JOSEPH ARKINS, OF CHICAGO, ILLINOIS.

IMPROVEMENT IN WEATHER-STRIPS.

Specification forming part of Letters Patent No. **179,756**, dated July 11, 1876; application filed June 17, 1876.

To all whom it may concern:

Be it known that I, JOSEPH ARKINS, of Chicago, in the county of Cook and State of Illinois, have invented a new and valuable Improvement in Weather-Strips; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a horizontal section of my weather-strip, and Fig. 2 is a longitudinal vertical sectional view of the same. Figs. 3, 4, and 5 are detail views of the weather-strip.

This invention relates to weather-strips for windows; and it consists in a parting strip or bead provided on one side with a rubber weather-strip for the upper sash, and on the other side with a similar strip for the lower sash, the two weather-strips being united at the top of one and the bottom of the other by a cross-strip, which corresponds in position to the meeting-rail, and protects the open space thereat.

In the annexed drawings, A designates the window-frame; B, the upper sash, and B' the lower sash. C is the parting-bead, which is longitudinally grooved on one side at c, and

on the other side at c'. Groove c begins at the top, and runs down as far as the meeting-rail of the sash, while the other groove begins at the same point on the opposite side of parting-bead C, and runs down to the bottom of said parting-bead. These two grooves are connected by a cross-groove directly through the face of the bead. A weather-strip of rubber, D, is set into these grooves, so as to extend obliquely outward on either side, and straight outward horizontally from the groove in front. It thus constitutes, in effect, three weather-strips, one protecting each sash and one the space at the meeting-rail.

What I claim as new, and desire to secure by Letters Patent, is—

In combination with weather strip or strips, a parting-strip grooved on one side in its upper part, and on the other side in its lower part, and provided with a cross-groove opposite the meeting-rail, substantially as and for the purpose set forth.

In testimony that I claim the above I have hereunto subscribed my name in the presence of two witnesses.

JOSEPH ARKINS.
